(57) **CLAIM**

The ornamental design for a tap off box, as shown and described.

DESCRIPTION

FIG. 1 is a perspective view of a tap off box;
FIG. 2 is a front elevational view of the tap off box of FIG. 1;
FIG. 3 is a rear elevational view of the tap off box of FIG. 1;
FIG. 4 is a right side elevational view of the tap off box of FIG. 1;
FIG. 5 is a left side elevational view of the tap off box of FIG. 1;
FIG. 6 is a top plan view of the tap off box of FIG. 1; and,
FIG. 7 is a bottom plan view of the tap off box of FIG. 1. The broken lines shown in the drawings are for purposes of illustrating portions of the tap off box that form no part of the claimed design.

1 Claim, 7 Drawing Sheets
